FIG. 1.

FIG. 2.

INVENTOR:

JOHN R. MOODY,
BY: Otto H. Rineger,
his Atty.

UNITED STATES PATENT OFFICE.

JOHN R. MOODY, OF LOS ANGELES, CALIFORNIA.

HINGE.

1,423,812.

Specification of Letters Patent. Patented July 25, 1922.

Application filed October 24, 1921. Serial No. 509,993.

To all whom it may concern:

Be it known that I, JOHN R. MOODY, a citizen of the United States, residing at Los Angeles, in the county of Los Angeles and 5 State of California, have invented a new and useful Hinge, of which the following is a specification.

This invention relates to devices for swingably connecting two members at adjoining 10 edges.

One of the objects of this invention is to facilitate a hanging and removing of doors and windows.

Another object is to provide removable 15 pins for a hinge, a portion of the pin to be placed into position for partly engaging the two hinge members, the main portion of the pins to be inserted after the two hinge members have become engaged.

20 Another object is to make the connecting pin between two hinge members of several sections.

Other objects will appear from the following description and appended claims as well 25 as from the accompanying drawing, in which—

Fig. 1 is a side elevation of a hinge embodying the invention.

Fig. 2 is a detail side elevation of the lower 30 removable pin.

The two hinge members 3 and 4 are provided with the eyes or knuckles 5, 6, 7, 8 and 9. Of course, more or less knuckles can be provided for different sizes of hinges and 35 according to the requirements of a hinge.

In one or more of the knuckles of one hinge-member a removable pin is inserted with a short engaging end for the opposite hinge member. A removable pin of this 40 sign or form is illustrated in detail in Fig. 2. The one end or portion 10 of the pin is normally inserted into one of the knuckles so that the shoulder portion 11 rests on the knuckle, leaving the short end 12 free to engage with 45 one of the knuckles of the opposite or second hinge member. Such a slight engagement of the two hinge members is sufficient to hold the two hinge members in proper relation with one another until the common pin 50 is inserted.

Windows and doors, especially, are very often moved and removed from their proper places and taken from the hinges. With the common hinges, in replacing a window 55 or door, the hinge members on the window or door must be brought into alignment with

the hinge members on the frame work before the hinge pin can be inserted, which is a feat not always accomplished by one person. Inserting a small pin into one of the 60 knuckles of each hinge member on the frame-work allows a hanging of a door or window to a suitable extent that the person hanging the article may have the hands free for inserting the main pin through the several 65 hinges.

A space is provided between the knuckles 6 and 7 and between the knuckles 8 and 9, as indicated at 13. This allows a lifting of the hinge member 4 in suitable relation to 70 the hinge member 3 to free the knuckle 6 from the short pin end 12. If a moving of the hinge members 3 and 4 is to be avoided while the hinge members are in engagement, washers 14 are disposed between the 75 knuckles before the main pin 15 is inserted.

To disengage this hinge, the main pin 15 is first removed, allowing a removing of the washers 14, which frees the hinge member 4 to be lifted from engagement with the 80 short end 12, and the short pin 10 may then also be withdrawn from the knuckle 5.

The knuckle just above the short pin 12 is preferably countersunk or widened at the lower end to some extent, so that the hinge 85 knuckle will easily engage over the end 12 of the pin.

Having thus described my invention, I claim:

1. In a hinge, a pin made of sections, one 90 of the sections to be inserted into one of the knuckles of one of the hinge members having a short engaging end to engage slightly with a knuckle of the opposite hinge member, and the main section having a shape to 95 fit through the remaining portion of the hinge knuckles.

2. In a hinge, a short engaging pin having one end to fit into one knuckle of one hinge member and having a short engaging end 100 normally projecting out of the first named knuckle for preliminary and slight engagement with a knuckle of the second hinge member preparatory to inserting a regular pin for permanent engagement of the two 105 opposite hinge members.

3. In a hinge, a short engaging pin having one end to fit into one knuckle of one of the hinge members and having a shouldered portion to rest on the end of the first-named 110 knuckle and having furthermore a short engaging end projecting beyond the shouldered

portion for preliminary and slight engagement with a knuckle of the second hinge member.

4. In a hinge consisting of two oppositely arranged hinge members, each of the hinge members having knuckles normally spaced when in engagement, a short engaging pin consisting of a portion to fit into one knuckle of one hinge member and another portion of 10 a length less than the space between the opposite knuckles to engage with a knuckle of the second hinge member, and another pin to fit through the remaining portion of the knuckles of the two hinge members.
- 15 5. In a hinge, two oppositely arranged hinge members, each of the hinge members having knuckles normally spaced when in engagement, a short engaging pin to fit into one knuckle of one hinge member and also 20 for a short distance into a knuckle of the second hinge member, and another pin to fit through the remaining portion of the knuckles of the two hinge members.
- 25 6. In a hinge, two oppositely arranged hinge members, each of the hinge members having knuckles normally spaced when in engagement, a short engaging pin to fit into one knuckle of one hinge member and also to a short extent into a knuckle of the second

hinge member for preliminary aligning the 30 opposite hinge members, the second-named knuckle having a shape to easily engage over the end of the said pin, and another pin to fit through the remaining portion of the knuckles of the two hinge members. 35

7. In a hinge, two oppositely arranged hinge members, each of the hinge members having knuckles normally spaced when in engagement, a short engaging pin fitting into one knuckle of the one hinge member and 40 having a shouldered portion to rest on the first-named knuckle and having furthermore a short engaging end projecting beyond the shouldered portion for preliminary and slight engagement with a knuckle of the 45 second hinge member, washers inserted in the space between the several knuckles, and another pin to fit through the remaining portion of the knuckles of the two hinge members. 50

In testimony that I claim the foregoing as my invention I have signed my name in the presence of two subscribing witnesses.

JOHN R. MOODY.
